CLAIM

The ornamental design for a loudspeaker, as shown and described.

DESCRIPTION

FIG. 1 is a top, front, right side isometric view of a loudspeaker, showing my new design;

FIG. 2 is a top, rear, left side isometric view thereof;

FIG. 3 is a front view thereof;

FIG. 4 is a rear view thereof;

FIG. 5 is a right side view thereof;

FIG. 6 is a left side view thereof;

FIG. 7 is a top plan view thereof, shown in enlarged scale, and the top plan view of FIGS. 9 and 12 being identical thereof;

FIG. 8 is a bottom plan view thereof, shown in enlarged scale, and the top plan views of FIGS. 9 and 12 being identical thereof;

FIG. 9 is a top, front, right side isometric view thereof;

FIG. 10 is a left side view thereof;

FIG. 11 is a rear view thereof;

FIG. 12 is a top, front, right side isometric view thereof, shown with the top extended and the acoustic lens is not in the deployed condition;

FIG. 13 is a top, rear, left side isometric view thereof;

FIG. 14 is a front view thereof;

FIG. 15 is a right side view thereof; and,

FIG. 16 is a left side view thereof.

The broken lines in the figures illustrate the portions of the design that form no part of the claimed design.
